UNITED STATES PATENT OFFICE.

MELANCTHON P. SIFFERT, OF NAVARRE, OHIO.

ROUTING-RACK.

1,372,100.

Specification of Letters Patent. Patented Mar. 22, 1921.

Application filed December 26, 1919. Serial No. 347,626.

To all whom it may concern:

Be it known that I, MELANCTHON P. SIFFERT, a citizen of the United States, residing at Navarre, in the county of Stark and State of Ohio, have invented a new and useful 5 Routing-Rack, of which the following is a specification.

This invention relates to routing racks and more especially to a rotatable rack made 10 up of independently rotatable sections especially adaptable for use in post offices for routing mail.

The objects of the invention are to provide a rack made up of a plurality of independently rotatable sections, each section 15 comprising a circular case provided with a plurality of radial compartments adjustable in width; to provide means for normally holding each section against rotation 20 and to allow each section to be rotated independently of the other sections and to generally improve and simplify constructions of this character.

With these objects in view the invention 25 consists in the novel construction and arrangement of parts, hereinafter described, illustrated in the accompanying drawings, and particularly pointed out in the appended claims, it being understood that various 30 changes in the form, proportions, size and minor details of construction may be made within the scope of the appended claims, without departing from the spirit or sacrificing any of the advantages of the invention. 35

The invention thus set forth in general terms is illustrated in the accompanying drawings forming part hereof, in which—

Figure 1 is a plan view of a filing rack 40 embodying the invention, parts being broken away for the purpose of illustration.

Fig. 2 is a side elevation of two units of the rack for the purpose of illustration.

Fig. 3 is a detail perspective view of one 45 of the sections of the standard which carries the brake mechanism.

Fig. 4 is a longitudinal sectional view through the brake mechanism.

Fig. 5 is a detail perspective view of the 50 spring pressed plunger used in the brake mechanism.

A practical embodiment of the invention is disclosed in the accompanying drawings, forming a part of this specification in which 55 similar numerals of reference indicate cor-

responding parts throughout the several views.

At 1 is shown a table or any other suitable support upon which the rack may be mounted. Screwed or otherwise attached to the 60 table is a metal face plate 2 carrying a concentric stud 3 which is received into the bearing socket 4 of a similar face plate 5 attached to the under surface of the lower section 6 of the rack. The lower section is 65 thus rotatable upon the table or other support upon which it is mounted.

Each section of the case comprises the upper and lower spaced circular top and bottom walls 7 and 8 respectively which are 70 connected together by means of the hub portion 9. Radial grooves 10 being provided in the upper and lower members 7 and 8 and communicating with vertical grooves 11 in the hub 9 for the reception of the partitions 12 by means of which the compartments 13, for the reception of mail or the like are provided.

The lower section 6 has connected to its upper wall 7 a face plate 2 upon which is 80 rotatably mounted a face plate 5 carried by the upper section 14 which is constructed in the same manner as the lower section and is provided upon its upper face with the face plate 2 for the attachment of another 85 section if desired. It will be noted that the partitions 12 may be placed in any desired grooves 10, thereby providing any desired size of compartment 13 which may be necessary to accommodate the mail for any one 90 patron.

The lower section 15 of the standard which carries the brake mechanism for the sections of the rack is connected to the table by means of screws 16 or the like. The 95 tubular casing 17 is provided with the flange portion 18 and connected by screws 19 and the like to the standard 15 and slidably mounted within the tubular casing is the plunger 20 having a collar 21 fixed thereon, 100 a coil spring 22 being located around said plunger tending to normally urge the shoe 23 into engagement with the periphery of the lower wall 8 of the adjacent section of the rack.

The upper end of the standard section 15 is provided with a socket 24 which receives the boss 25 upon the lower end of the standard 26 a set screw 27 holding said standard sections in fixed relation. The section 26 110

is also provided with a brake mechanism of the same construction as that carried by the section 15 and is provided in its upper end with a socket 24 arranged to receive the 5 boss 25 of the next higher section.

Although only two sections of the rack are illustrated in the accompanying drawing it is of course understood that any desired number of sections may be added in 10 the same manner, each section being normally held against rotation by means of brake mechanism acting thereon and arranged to be moved independently of the other sections. Although the device has 15 been described as being best adapted for use as a mail rack for routing mail it will of course be seen that the device is applicable for filing or displaying any character of small articles where it is desired to place 20 the largest number of articles in the smallest space.

Although the drawings and above specification disclose the best mode in which I have contemplated embodying my invention 25 I desire to be not limited to the details of such disclosure, for, in the further practical application of my invention, many changes in the form and construction may be made, as circumstances require or experience suggests, without departing from the spirit of 30 the invention, within the scope of the appended claims.

I claim:

1. A filing rack including a plurality of superposed, concentric, independently rotatable filing sections, a standard parallel to the axis of the filing sections and a brake mechanism carried by the standard and engaging the periphery of each filing section, said brake mechanism normally holding each section against rotation independent of the other sections and at the same time allowing each section to be manually rotated independently of the other section. 35

2. A filing rack including a plurality of superposed, independent, rotatable filing sections, a standard parallel to the axis of the filing sections comprising a plurality of detachable sections corresponding to the filing sections and a brake mechanism carried 40 by each standard section and engaging the periphery of the adjacent filing section. 45

3. A filing rack including a plurality of superposed concentric independently rotatable circular filing sections, a plurality of superposed standard sections parallel to the axis of the filing sections and a brake mechanism carried by each standard section and engaging the periphery of the adjacent filing section. 55

In testimony that I claim the above, I have hereunto subscribed my name.

ELANTHON P. SIFFERT.
